DEVICE FOR DETERMINING SHRINKAGE
IN GARMENTS

Ben Sidney Pollock, Fort Smith, Ark.

Application March 31, 1942, Serial No. 437,052

3 Claims. (Cl. 33—2)

My invention relates to improvements in devices for determining shrinkage in garments, the principal object in view being to provide a simply constructed, easily operated, inexpensive device for checking measurements of dresses and the like before and after dry cleaning to ascertain whether or not shrinkage has occurred.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in front elevation of my improved garment checking device, in its preferred embodiment,

Figure 2 is a view in side elevation,

Figure 3 is a view in vertical section taken on the line 3—3 of Figure 1,

Figure 4 is a view in rear elevation, and

Figure 5 is a view in transverse section taken on the line 5—5 of Figure 1.

Referring to the drawings by numerals, according to my invention, an elongated rectangular frame is provided for suspension, in any suitable manner, in upended position and which includes a panel 1 of the requisite size for hanging of a dress of any size alongside the front of the same with substantial clearance above the top and bottom of the dress. Extending rearwardly around the edges of the panel 1 are top, bottom and side bars, 2, 3 and 4, respectively, forming an open-back housing for a purpose presently seen. Extending forwardly of the panel 1 around the edges of the frame are molding strips including side pieces 5 each provided in the inner side face thereof with a vertically extending guide groove 6.

A measuring bar 7 extends lengthwise across the front face of the panel 1 with its ends fitted between the side pieces 5 with a slight clearance, said bar being suitable spaced forwardly of the panel 1 to obviate frictional contact with the same. A pair of plate-like shoes 8 suitably fixed to the rear face of the measuring bar 7 adjacent the opposite ends thereof and extending into the guide grooves 6 provide for vertical sliding adjustment of said bar 7 in a fixed path.

A pair of cables 9 suspend the measuring bar 7, said cables being fixed at ends thereof in any suitable manner to the shoes 8 and trained over a pair of pulleys 10 suitably mounted in the upper corners of the panel 1 to rotate in apertures 11 in

said panel. The other ends of the cables 9 hang pendent behind the panel 1 in the housing formed by the bars 2, 3 and 4, and have suitably secured thereto counterweights 12.

5 Means are provided for suspending a dress, or other garment alongside the front face of the panel 1 in front of the measuring bar 7 and comprising the following: In the vertical center of the panel 1 is a yoke 13 upstanding from the top bar 2 and described molding. A coil spring 14 is suitably secured at one end in the top of the yoke 13 to depend through a notch 15 in the described molding alongside the front of the panel 1. The coil spring 14 is provided with a lower 15 end eye 16 for coupling to the hook 17 of a conventional wire clothes hanger 18 adapted to be suspended by said spring against the front face of the panel 1 to lie parallel with said face. A pair of roller-like stops 19 are provided on the front face of the panel 1 in laterally spaced relation upon opposite sides of the vertical center of said panel 1 to stabilize the hanger 18 and limit upward movement of the same under the action of the spring 14, the arrangement being 20 such that said hanger will be suspended adjacent the top of said panel with its diagonal side resting against said rollers. In the vertical center of the panel 1, on the front face thereof, a vertically extending half-inch scale is provided, the 25 half-inch graduations of which are designated in successive series 0 to 9, with the numbers increasing in value in each series downwardly. The described vertical scale extends to the bottom of the panel 1 from a point intermediate the 30 stops 19. The measuring bar 7 is provided along its top and bottom edges, on its outer front face, with half-inch scales, each having a zero graduation at the transverse center of the bar and being numbered in successive series ranging from 0 to 9, with the numbered calibrations increasing 35 in value in each series outwardly toward each end of the bar. Thus, the two horizontal scales are uniform in measurement relation to the aforementioned vertical scale. Also, the bar 7 is of a width corresponding to the standardized 10-inch 40 measurements between the waist and hip line of dresses. Further, the innermost series on each side of the center zero may be colored the same and in alternately different colors in each series 45 for contrast to facilitate reading the same, but since such coloring forms no part of the invention, it has not been illustrated in the drawings.

In the use of the described invention, before a dress, or similar garment, is cleaned, it is hung on the hanger 18 and the latter attached to the

spring 14 which is stretched so that the hanger may be placed underneath and against the stops 19 and thereby establish a standard position on the device for every dress. With the dress centered relative to the vertical scale, the front and back bottom hem of the garment or dress are then adjusted until they hang at the same level, and this level, or length of the dress, is read on the vertical scale and recorded as a single digit, for instance 9, if that be the reading. The measuring bar 7 may next be placed in position such that the upper edge thereof is behind the bottom of the armholes and a reading taken at this point, on the upper scale of the bar from the same numbers appearing at both sides of the dress. The reading may be recorded as a single digit, for instance 4. Next, the measuring bar is lowered behind the dress until the upper edge scale registers with the waist line of the dress. The dress being centered, the width of the waist is checked on both sides of the said upper edge scale and like numbers on each side and also recorded as a single digit, such, for instance, as 3, assuming that to be the reading. We now have the recording of the three measurements as 943. Next, without moving the measuring bar, the hip line measurement is checked on the lower edge scale of said bar in the same manner as the waist measurements. If the measurement reading be 6, it may be recorded after the other three measurement recordings and we now have the measurement reading 9436. After dry cleaning and finishing, the described measurement operation is repeated to determine whether shrinkage has occurred. This may be done on the same or another similar apparatus.

The foregoing will, it is believed, suffice to impart a clear understanding of my invention without further explanation.

Manifestly, the invention as described is susceptible of modification without departing from the inventive concept, and right is herein re-

served to such modifications as fall within the scope of the subjoined claims.

What I claim is:

1. In a device of the class described a panel 5 adapted to be arranged in upright position, means mounted on said panel for suspending a dress hanger in front of said panel and in centered relation thereto, and means for checking the width of the dress at the waist and hip line 10 concurrently comprising a scale bar mounted on said panel for vertical traveling movement behind the dress, the first-mentioned means comprising a coil spring suspended at the top of the panel in front of the same for tensioning 15 downwardly and for attachment of the dress hanger thereto, and a pair of stops on said panel at opposite sides of said spring, respectively, for limiting upward movement of the hanger under reaction of the spring.
2. In a device of the class described a panel 20 adapted to be arranged in upright position, means mounted on said panel for suspending a dress hanger in front of said panel in centered relation thereto, and means for checking the width of the dress at the waist and hip line concurrently comprising a scale bar mounted on said panel for vertical traveling movement behind the dress, the mounting for said bar comprising counter-balancing devices therefor.
3. In a device of the class described a panel 25 adapted to be arranged in upright position, means mounted on said panel for suspending a dress hanger in front of said panel in centered relation thereto, and means for checking the width of the dress at the waist and hip line concurrently comprising a scale bar mounted on said panel for vertical traveling movement behind the dress, and said bar being of a width corresponding to 30 the average distance between the waist and hip 35 lines of a dress and having scales along both side edges thereof.

BEN SIDNEY POLLOCK.
